UNITED STATES PATENT OFFICE.

LOUIS J. SCHEINMAN, OF NEW YORK, N. Y.

GARMENT AND BELT THEREFOR.

1,286,798.

Specification of Letters Patent.

Patented Dec. 3, 1918.

Application filed June 28, 1916. Serial No. 106,298.

To all whom it may concern:

Be it known that I, LOUIS J. SCHEINMAN, a citizen of the United States, and resident of the borough of Manhattan, city, county, 5 and State of New York, have invented new and useful Improvements in Garments and Belts Therefor, of which the following is a specification.

My invention relates to garments and 10 more particularly to skirts or the like having gathered portions and has for its object to provide an arrangement in which a pronounced and graceful draped and gathered effect is produced and maintained and in 15 which the garment when worn hangs free in a graceful and fashionable manner or is efficiently supported on the wearer in the desired way. My improvement further contemplates a garment which will fit different 20 figures within certain limits without requiring any alteration and without seriously disturbing the graceful and fashionable appearance and the intended set thereof. A further object of my invention is to provide 25 an improved belt construction which may be readily incorporated in the garment and whereby the above desired features are positively attained in a simple and efficient manner. My improvement will be fully described hereinafter and the features of novelty will be pointed out in the appended 30 claims.

Reference is to be had to the accompanying drawings which for the purposes of description and illustration show an example of my improvement and in which Figure 1 is a perspective front view of the upper portion of my improved skirt; Fig. 2 is a perspective rear view thereof; Fig. 3 is a perspective view of an example of my improved belt or waistband and Fig. 4 is a detail section on the line 4—4 of Fig. 1.

In the illustrated example my improved belt or waistband which I have designated 45 as a whole with the numeral 5, comprises two main sections 6 and 7 which are provided with coöperating fastening devices 8 and 9 whereby the free ends of said sections 6 and 7 may be detachably connected together. The opposite ends of said sections 6 and 7 in the illustrated example are spaced apart and are connected with each other by auxiliary strips of material 10 and 11 which extend between the main sections 6 and 7 50 and in the illustrated example have their opposite ends secured thereto in any suitable manner as by sewing. The upper auxiliary strip 10 is relatively narrow and throughout its length is spaced from the relatively wider and lower auxiliary strip 11 whereby a free 55 space 12 is formed between both sections 10 and 11 as shown in Fig. 3. The parts are so designed in the illustrated example that the auxiliary strips 10 and 11 form substantially the back of the belt and 60 in use are located at the back of the garment. In the complete garment the skirt 13 is attached to the main sections 6 and 7 by stitches 14 or otherwise, the line of attachment extending parallel and in close proximity to the upper edges of said main sections 6 and 7 and preferably though not necessarily leaving all parts of the latter and of the skirt below the stitching 14 free and disconnected from each other as shown in 65 Fig. 4. The stitching 14 further terminates at a distance from the free ends of the sections 6 and 7 so that these free ends are also loose from the skirt and thus easily connected together and disconnected from each 70 other. In practice the free ends of the sections 6 and 7 are located in registry with the placket 15 of the skirt or equivalent opening of any other garment closed by means of fastening means 16 and 17, it being 75 understood that the sections 6 and 7 are preferably always constructed in such a manner that this result is obtained and that the location of the placket 15 or corresponding opening to a certain extent determines the 80 arrangement of the said sections. In the arrangement shown the upper auxiliary strip 10 is contained in a pocket 18 which may be formed by means of a length of tape or other material 19 having its opposite edges and 85 ends secured to the skirt material by stitches 20 as shown in Figs. 1 and 4, and in any case is of a vertical width corresponding 90 substantially to the width of the strip 10, the edges of which are thus frictionally engaged by the upper and lower walls of the pocket 18 as illustrated in Fig. 4. The skirt material is gathered upon said strip 10 between the ends of the sections 6 and 7 as 95 shown in Fig. 1, this effect being efficiently 100 produced for instance by constructing the strips 10 and 11 of elastic material and then forming the pocket 18 about said strip 10 while the latter is stretched or under a tension. As the said strips 10 and 11 return to 105 normal position the material, if this arrangement is followed, will be evenly and 110

harmoniously gathered between the ends of the sections 6 and 7 owing to the frictional engagement between the strip 10 and the walls of the pocket. It will be seen that in 5 the described and illustrated arrangement the skirt is supported from the upper edges of the sections 6 and 7 and from the strip 10 and that the strip 11 is inside of the skirt and forms a continuation of the sections 6 10 and 7 whereby the latter are maintained in the desired positions against disarrangement. If the strips 10 and 11 are constructed of elastic material the lower strip 11 in practice will hold the belt firmly against the 15 body of the wearer and will thus leave the skirt free to hang gracefully from the upper edge whereby a pronounced draped effect is produced which gives to the skirt the desired fashionable and expensive appearance, 20 or any other garment with which the belt may be combined will be efficiently and properly supported. This lower strip 11 will in any case, even if made of non-elastic material, bring about these results, although 25 possibly to a somewhat lesser degree. In some cases this strip 11 may be replaced by other arrangements producing equivalent results or operating in substantially the same manner. If desired, a tongue 21 may extend 30 between and be connected with the strip 11 and the pocket forming tape 19 to prevent unintended separation of these elements under the strains produced when the garment is worn.

35 It will be apparent that the relatively thin strip 10 and relatively wider strip 11 may be otherwise combined with the sections 6 and 7 than shown and also that the same narrow and wider strips may be produced by 40 constructing the belt in other ways than that illustrated. It will also be obvious that the particular relative dimensions in the strips as well as the number thereof may be changed to meet the requirements of each case and it 45 is to be understood that by the term "strips" I do not mean merely separate elements connected with the belt sections but on the contrary that I mean to include any elements included in a belt construction whereby the 50 same or equivalent results may be obtained. In addition to this, it will be apparent that the entire belt including the sections 6 and 7 may be constructed of elastic material or that the entire belt including the strips 10 55 and 11 may comprise substantially non-elastic material.

When for instance the strips 10 and 11 are constructed of elastic material, they will, in addition to producing an effective and 60 ornamental gathering of the garment material at a predetermined point in said garment, make the same adjustable within certain limits and thus capable of being successfully worn by persons with figures of different 65 dimensions without alteration and with-

out appreciably interfering with or destroying either the effect at the gathered portion of the garment or the entire appearance thereof.

The cost of alterations and the time incident thereto is thus saved with my improvement and a large range of sizes may be efficiently satisfied with minimum varieties of my improved garment.

My invention holds up and supports the 75 garment in the intended manner and without discomfort to the wearer and in a simple and cheap manner provides a skirt which has the appearance of a high class and expensive garment. My improved belt may be readily 80 and cheaply produced in a variety of ways and forms and may be supplied as a separate article of merchandise and sold for instance to garment makers ready to be embodied in the garments.

85 Various changes in the specific form shown and described may be made within the scope of the claims without departing from the spirit of my invention.

90 I claim:

1. The combination of belt sections, a garment secured thereto and provided with a pocket extending circumferentially thereof, and a plurality of strips extending between said belt sections and located one above the other, one of said strips being located within said pocket, the normal length of said pocket being greater than the length of said strip, whereby a gathering of the garment material is produced and maintained between said belt 100 sections and said other strip being outside of said pocket on the inside of said garment.

2. The combination of belt sections, a skirt secured thereto only at its upper edge and provided with a pocket extending circumferentially of said skirt, a relatively narrow strip of elastic material extending between opposed ends of said belt sections and located within said pocket, the normal length of said narrow strip being less than the length of the 110 pocket whereby a gathering of the skirt material is produced and maintained between said opposed ends of said belt sections and a relatively wider strip of elastic material extending between said opposed ends of the 115 belt sections and spaced from the narrow strip throughout the space between said belt sections, said wider strip being located outside of said pocket and free from said garment.

120 3. The combination of belt sections, a skirt secured thereto only at its upper edge and provided with a pocket extending circumferentially of said skirt, a relatively narrow strip of elastic material extending between 125 opposed ends of said belt sections and located within said pocket, the normal length of said narrow strip being less than the length of the pocket whereby a gathering of the skirt material is produced and maintained between 130

said opposed ends of said belt sections, a relatively wider strip of elastic material extending between said opposed ends of the belt sections and spaced from the narrow strip 5 throughout the space between said belt sections, said wider strip being located outside of said pocket and free from said garment, and a tongue connected with said wider strip and with said pocket whereby separation in 10 a vertical direction is arrested.

4. A belt adapted for combination with a garment for supporting same and comprising two relatively wide sections spaced from each other in a direction lengthwise of the 15 belt and two relatively narrow sections transversely spaced from each other and extending between the opposed ends of said relatively wide sections, said narrow sections having their opposed ends permanently 20 secured to the ends of said wide sections and being free and disconnected from each other at all points between said wide sections prior to incorporation in a garment, one of said narrow sections providing a means upon 25 which a portion of said garment may be draped.

5. A belt adapted for combination with a garment for supporting same and comprising two relatively wide sections spaced from 30 each other in a direction lengthwise of the belt, and two relatively narrow sections

transversely spaced from each other and constituting permanent continuations of said wide sections to complete the belt and form the back thereof, said narrow sections being 35 free and disconnected from each other at all points throughout their length between said wide sections prior to incorporation in a garment and being one transversely wider than the other, the narrower one of said two 40 relatively narrow sections providing a means upon which a portion of the garment may be gathered.

6. A belt adapted for combination with a skirt for supporting same and comprising 45 two main sections spaced from each other and forming the ends of the belt, and two intermediate elastic sections extending in parallel and transversely spaced relation to each other between said main sections to form the 50 back of the belt and having their ends permanently secured to said main sections, said intermediate sections being free and disconnected from each other at all points throughout their length between said main sections 55 prior to incorporation in a garment, one of said intermediate sections providing a means upon which a portion of said skirt may be gathered.

In testimony whereof I have hereunto set 60 my hand.

LOUIS J. SCHEINMAN.
